US00D824189S

(12) **United States Design Patent** (10) **Patent No.:** **US D824,189 S**
(45) **Date of Patent:** **** Jul. 31, 2018**

(54) **SHOWER CADDY**

(71) Applicant: **simplehuman, LLC**, Torrance, CA
(US)

(72) Inventors: **Frank Yang**, Rancho Palos Verdes, CA
(US); **Di-Fong Chang**, Torrance, CA
(US); **Myk Lum**, Irvine, CA (US);
Adam Wade, Rancho Santa Margarita,
CA (US)

(73) Assignee: **simplehuman, LLC**, Torrance, CA
(US)

(**) Term: **15 Years**

(21) Appl. No.: **29/594,906**

(22) Filed: **Feb. 23, 2017**

(51) LOC (11) Cl. **23-02**

(52) U.S. Cl.

USPC **D6/525**

(58) **Field of Classification Search**

(57) **CLAIM**

The ornamental design for a shower caddy, as shown and described.

DESCRIPTION

FIG. 1 is a top, front, left-side perspective view of a shower caddy embodying our design;

FIG. 2 is a bottom, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

All features in broken line form no part of the claimed subject matter.

1 Claim, 6 Drawing Sheets
